UNITED STATES PATENT OFFICE.

ROBERT D. ANDREWS, OF BOSTON, MASSACHUSETTS.

DESIGN FOR A PARLOR OR HEATING STOVE.

SPECIFICATION forming part of Design No. 15,810, dated February 17, 1885.

Application filed December 17, 1884. Term of patent 7 years.

To all whom it may concern:

Be it known that I, ROBERT D. ANDREWS, a citizen of the United States, residing at Boston, in the county of Suffolk and State of Massachusetts, have invented and produced a new and original Design for Parlor or Heating Stoves, of which the following is a specification, reference being had therein to the accompanying photographs, forming a part thereof, numbered and marked Figures 1, 2, 3.

Fig. 1 is a bird's-eye view of the top of my newly-designed parlor or heating stove. Fig. 2 is a front view, and Fig. 3 is a three-quarter view, of the same.

The leading features of my design consist of a parlor or heating stove with a top, A, front plate, B B' B', doors C D, top of base E, side-rail brackets F F, skirting G, legs H, and panels I, ornamented as follows: The top consists of a plain dome, a, springing from a wider and flatter one, A, which is elaborately ornamented in low relief with sprigs of hawthorn in blossom, divided into sections and bordered by bands of blossoms, as shown in Fig. 1, the whole surrounded by a fine beaded molding. The front plate, B B' B', is ornamented by sprigs of conventionalized foliage, stems, and flowers springing from the top of the clinker-door N, and the corners of which, B' B', are ornamented by figures of a crouching rabbit, all in low relief. The feed-door C is ornamented

at the corners by hawthorn-blossoms and united by stems and foliage of the same, forming a garland around the center panel, as shown in Figs. 1, 2. The clinker-door N is surrounded by an ornamented border, K, of a conventional Greek design. The base is ornamented on the top E by hawthorn foliage and blossoms, at the sides by panels I, ornamented by the same design, all in low relief, and also by the conventionalized storks F, which latter form the side-rail brackets or supports. The ash-door D is ornamented by sprigs of conventionalized stems, foliage, and blossoms; the legs H by a medallion in the form of a hawthorn-blossom inclosed in a ribbon springing out on either side in the form of a scroll at the juncture of the legs and skirting G, and the latter by interlacing branches of the hawthorn flowers and foliage.

I claim—

The design for a stove of the shape shown, having its top front plate, doors, side panels, brackets, and skirting ornamented by figures or conventionalized flowers, vines, leaves, and stems, as shown and described.

In testimony whereof I affix my signature in presence of two witnesses.

ROBERT D. ANDREWS.

Witnesses:

DANIEL C. LINSCOTT,
A. E. PILLSBURY.
